US0D1106761S

(12) **United States Design Patent** (10) Patent No.: **US D1,106,761 S**
(45) Date of Patent: ** *Dec. 23, 2025

(54) **MUG**

(71) Applicant: **YETI Coolers, LLC**, Austin, TX (US)

(72) Inventors: **Dustin R. Bullock**, Austin, TX (US); **Alexander Munao**, Austin, TX (US)

(73) Assignee: **YETI Coolers, LLC**, Austin, TX (US)

(*) Notice: This patent is subject to a terminal disclaimer.

(**) Term: **15 Years**

(21) Appl. No.: **29/886,667**

(22) Filed: **Mar. 10, 2023**

(51) LOC (15) Cl. **07-01**

(52) U.S. Cl. **USPC** **D7/536**

(58) **Field of Classification Search**

CLAIM

The ornamental design for a mug as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, right perspective view of a mug showing our new design;
 FIG. 2 is a rear view thereof;
 FIG. 3 is a front view thereof;
 FIG. 4 is a right side view thereof;
 FIG. 5 is a left side view thereof;
 FIG. 6 is a top view thereof;
 FIG. 7 is a bottom view thereof;

FIG. 8 is a bottom, rear, left perspective view thereof;
 FIG. 9 is a top, front, right perspective view of a first alternative claimed configuration mug showing our new design;
 FIG. 10 is a rear view thereof;
 FIG. 11 is a front view thereof;
 FIG. 12 is a right side view thereof;
 FIG. 13 is a left side view thereof;
 FIG. 14 is a top view thereof;
 FIG. 15 is a bottom view thereof;
 FIG. 16 is a bottom, rear, left perspective view thereof;
 FIG. 17 is a top, front, right perspective view of a second alternative claimed configuration mug showing our new design;
 FIG. 18 is a rear view thereof;
 FIG. 19 is a front view thereof;
 FIG. 20 is a right side view thereof;
 FIG. 21 is a left side view thereof;
 FIG. 22 is a top view thereof;
 FIG. 23 is a bottom view thereof;
 FIG. 24 is a bottom, rear, left perspective view thereof;
 FIG. 25 is a top, front, right perspective view of a third alternative claimed configuration mug showing our new design;
 FIG. 26 is a rear view thereof;
 FIG. 27 is a front view thereof;
 FIG. 28 is a right side view thereof;
 FIG. 29 is a left side view thereof;
 FIG. 30 is a top view thereof;
 FIG. 31 is a bottom view thereof;
 FIG. 32 is a bottom, rear, left perspective view thereof;
 FIG. 33 is a top, front, right perspective view of a fourth alternative claimed configuration mug showing our new design;
 FIG. 34 is a rear view thereof;
 FIG. 35 is a front view thereof;
 FIG. 36 is a right side view thereof;
 FIG. 37 is a left side view thereof;
 FIG. 38 is a top view thereof;
 FIG. 39 is a bottom view thereof;
 FIG. 40 is a bottom, rear, left perspective view thereof;
 FIG. 41 is a top, front, right perspective view of a fifth alternative claimed configuration mug showing our new design;
 FIG. 42 is a rear view thereof;
 FIG. 43 is a front view thereof;
 FIG. 44 is a right side view thereof;
 FIG. 45 is a left side view thereof;
 FIG. 46 is a top view thereof;
 FIG. 47 is a bottom view thereof; and,
 FIG. 48 is a bottom, rear, left perspective view thereof.
 The dot-dash broken lines immediately adjacent to the shaded area define the bounds of the claimed design and form no part thereof. The broken lines depicting the remainder of the mug form no part of the claimed design. FIGS. 1-8 are shaded with stippling to indicate a contrast in appearance to that region and does not represent any particular color, material, texture or finish.
